OIL WELL STUFFING BOX

Charles Frederick Moseley, Bartlesville, Okla.
Application January 20, 1954, Serial No. 405,199

1 Claim. (Cl. 286—16)

This invention relates to packing glands, and more particularly, but not by way of limitation, to an improved stuffing box adapted for use around the polished rod of a producing oil well.

As it is well known in the oil industry, the majority of producing oil wells are pumped by use of a rod type pump. The pumping unit is installed in the bottom of the oil well and is actuated by a string of rods from the surface. The uppermost rod, which projects from the well head, is commonly called the polished rod. A packing gland or stuffing box is ordinarily secured to the well head around the polished rod to prevent a leakage of the pumped oil from around the polished rod. The stuffing boxes in use at the present time, and particularly stuffing boxes utilizing cone shaped packing rings or glands, have two compression or follower members to retain the packing rings in the desired position around the polished rod. The use of two followers unduly increases the length of the stuffing box unit and is cumbersome, particularly when replacing the packing rings of the box unit. Another common detriment in the present day stuffing boxes is the subjection of the packing rings to salt water and abrasive material clinging to the polished rod. These abrasives cause substantial wear to the packing rings resulting in frequent replacing of the rings. In addition, small particles will frequently be worn off of the packing rings and will work their way downwardly in the well to the pumping unit and impair the operation of the valves thereof.

The present invention contemplates a novel oil well stuffing box utilizing a single packing ring compression member to materially reduce the overall length of the stuffing box unit and facilitate replacement of the packing rings. This invention also contemplates the use of a novel packing gland in the lower end of the stuffing box to wipe abrasive material from the polished rod upon upward movement of the rod. The lower packing gland may also be provided with an oil reservoir chamber to provide a constant lubrication of the polished rod.

An important object of this invention is to reduce to a minimum the overall length of oil well stuffing boxes.

Another object of this invention is to provide a stuffing box utilizing a single packing ring follower or compression member.

Another object of this invention is to remove abrasive material from an oil well polished rod before the abrasive material can contact the packing rings of a stuffing box.

A further object of this invention is to prevent small particles worn off of packing rings from falling downwardly in an oil well and interfering with the operation of the pumping unit.

A still further object of this invention is to provide a simply constructed stuffing box which may be economically manufactured.

Other objects and advantages of the invention will be evident from the following detailed description, read in conjunction with the accompanying drawings, which illustrate my invention.

In the drawings:

Figure 1 is an elevational view of a novel stuffing box with a quarter section of the stuffing box removed.

Figure 2 is a vertical sectional view of a modified oil well stuffing box.

Figure 3 is a fragmentary vertical sectional view of the lower portion of a stuffing box.

2

Referring to the drawings in detail, and particularly Fig. 1, reference character 2 generally designates a novel oil well stuffing box comprising a tubular shaped housing or body 4 having the lower end 6 thereof reduced in diameter and externally threaded for connection with the well head (not shown). An oil well polished rod 8 extends through the central portion of the housing 4 and reciprocates therein as will be hereinafter set forth.

An internally threaded retaining ring 10 is secured to external threads 12 provided on the upper end 14 of the housing 4. The retaining ring 10 is retained in position on the threads 12 by a transverse locking screw 16 which extends into one of a plurality of vertical grooves 18 provided in the outer periphery of the housing 4. It will be apparent that when the locking screw 16 is inserted in one of the grooves 18, the retaining ring 10 cannot be threaded or unthreaded from the body 4. A pair of diametrically opposed lugs 19 are formed on the outer periphery of the retaining ring 10 to facilitate turning of the ring 10.

The retaining ring 10 extends upwardly above the upper end 14 of the body 4 and is provided with an inwardly projecting circumferential shoulder 20 on the upper end thereof for engaging a tubular shaped floating compression member or packing ring follower 22 loosely disposed around the polished rod 8. A circumferential shoulder or outward flange 24 is provided on the outer periphery of the compression member 22 to engage the shoulder 20 and retaining ring 10. The lower end 26 of the compression member 22 is tapered upwardly and inwardly in the manner of a cone and is adapted to retain a plurality of super-imposed packing rings 28 in the body 4 around the polished rod 8.

A pair of circumferential grooves 30 are formed in the lower end 26 of the compression member 22 to provide spaced concentric shoulders 32, 34 and 36. The shoulders 32 to 36 contact the uppermost packing ring 28 to impose a substantially uniform force over the entire area of the packing rings 28. Thus, the packing rings 28 will form an effective seal between the polished rod 8 and the inner periphery of the body 4. The uppermost groove 30 permits an expansion of the upper end of the uppermost packing ring 28 upon upward movement of the polished rod 8, thereby minimizing the damage to this packing ring upon reciprocation of the polished rod 8.

The packing rings 28 are substantially conical in configuration and are disposed in the body 4 as shown in Fig. 1 with the larger ends 38 thereof extending downwardly. The lowermost packing ring 28 rests on a bottom shoulder 40 of the body 4 provided by the reduction in diameter of the body 4.

Operation

The stuffing box 2 is assembled on the polished rod 8 as shown in Fig. 1 with the lower end 6 of the body 4 threaded engaged with the well head. The polished rod 8 reciprocates vertically in the usual manner and moves through the packing rings 28. In the event the well fluid begins leaking around the polished rod 8 and through the packing rings 28, the retaining ring 10 may be tightened on the threads 12. The downward movement of the retaining ring 10 is transmitted through the shoulders 20 and 24 and the compression member 22 to the packing rings 28. Thus the packing rings 28 will be compressed into tighter contact with the polished rod 8 and the inner periphery of the body 4.

A modified stuffing box generally indicated at 42 is shown in Fig. 2 and comprises a tubular body 44 having its lower end 46 reduced in diameter and externally threaded for engagement with a well head. The body 44 is tapered downwardly and inwardly at 48 to provide the lower reduced end 46. A polished rod 50 extends through the central portion of the body 44 in the usual manner. A novel packing gland 52 is inserted in the lower por-

tion of the body 44 adjacent the tapered portion 48. A portion 54 of the outer surface of the packing gland 52 is tapered to conform to the tapered portion 48 of the body 44 and provide a seat for supporting the packing gland 52. The upper end 56 of the packing gland 52 is tapered upwardly and inwardly to receive and support a plurality of super-imposed and conical shaped packing rings 58. The packing gland 52 is formed out of a resilient or flexible material, and is provided with a central vertical bore of a size to provide a tight fit around the polished rod 50.

The packing rings 58 are retained on the upper end 56 of the packing gland 52 by a tubular shaped compression member or follower 62 loosely disposed around the polished rod 50. The lower end of the follower 62 is tapered upwardly and inwardly and provided with a circumferential groove 64, thereby forming a pair of vertically and horizontally spaced circumferential shoulders 66 and 68. The shoulder 68 contacts the uppermost packing ring 58 in proximity with the lower larger end 70 thereof and the shoulder 66 contacts the uppermost packing ring 58 in proximity with the upper smaller end or tip 72 thereof. An annular groove 74 is also formed in the inner periphery of the follower 62 adjacent the shoulder 66 to permit expansion of the tip 72 of the uppermost packing ring 58.

An annular groove 76 is formed in the upper end of the follower 62 to receive a pair of diametrically opposed arms 78. The arms 78 depend from an apertured bracket 80 loosely surrounding the polished rod 50 and secured to the body 44 by bolts 82. The bolts 82 are adapted to thread into nuts 84 secured to the body 44 by brackets 86 on opposite sides of the body 44.

Upon reciprocation of the polished rod 50, all abrasive material clinging to the polished rod 50 is effectively removed by the packing gland 52, thereby preventing abrasive material from coming into contact with the packing rings 58. The packing rings 58 will be slightly deformed upon upward movement of the polished rod 50 and the upper end 72 of the uppermost packing ring 58 will expand into the groove 74. In the event the packing rings 58 become slightly worn and well fluid leaks upwardly around the polished rod 50, the packing rings 58 may be further compressed by tightening the bolts 82. It will be apparent that when the bolts 82 are tightened, the arms 78 will be moved downward to force the follower 62 in a downward direction and increase the pressure on the packing rings 58 through the medium of the shoulders 66 and 68. The spaced shoulders 66 and 68 provide a compression of the packing rings 58 into tight contact with both the inner periphery of the body 44 and the outer periphery of the polished rod 50.

A further modification of the stuffing box is shown in Fig. 3, wherein reference character 88 designates a tubular stuffing box body reduced in diameter and externally threaded at its lower end 90. The body 88 is tapered at 92 to form the reduced portion 90. An inwardly projecting circumferential shoulder 94 is formed in the body 88 opposite the upper end of the tapered portion 92. The usual polished rod 96 extends vertically through the central portion of the body 88.

A novel tubular shaped packing gland 98 formed out of a resilient, or flexible material is disposed in the lower portion of the body 88. The outer periphery of the packing gland 98 is provided with a tapered portion 100 formed in the same manner as the tapered portion 92 of the body 88. A circumferential groove 102 is formed in the outer periphery of the packing gland 98 and provides a circumferential flange 104 above the tapered portion 100. It will be apparent that the shoulder 94 forms a stop to contact the flange 104 and limit downward movement of the packing gland 98. The upper surface 106 of the packing gland 98 is tapered to conical form to receive a plurality of super-imposed conical shaped packing rings 108. The packing rings 108 may be retained on the surface 106 in sealing contact with the polished rod 96 and inner periphery of the body 88 by any suitable compres-

sion means (not shown), but preferably the type shown in Fig. 1 or 2.

A circumferential groove 110 of substantially semi-circular shape is formed in the inner periphery of the packing gland 98 substantially in the central portion thereof and provides a reservoir 112. In operation, the chamber 112 becomes filled with the well liquid and provides a constant supply of lubricant for the polished rod 96. In addition, particles worn from the inner periphery of the packing rings 108 will collect in the chamber 112 and will be prevented from falling into the well and interfering with the well pump (not shown). It will also be noted that the packing gland 98 will remove abrasive material from the polished rod 96 before it can contact the packing rings 108.

From the foregoing, it is apparent that the present invention provides a novel oil well stuffing box having a minimum length and utilizing a single packing ring follower or compression member. The use of a single packing ring follower, in addition to decreasing the overall length of the box, also facilitates tightening of the stuffing box and replacement of worn packing rings. Abrasive material is effectively removed from the polished rod before it can contact the packing rings and particles worn from a packing ring are effectively trapped and prevented from falling into the well. It is also apparent that the present invention provides a simply constructed oil well stuffing box which may be economically manufactured.

Changes may be made in the combination and arrangement of parts as heretofore set forth in the specification and shown in the drawings, it being understood that any modification in the precise embodiment of the invention may be made within the scope of the following claim without departing from the spirit of the invention.

What is claimed is:

35 A stuffing box for an oil well polished rod, said stuffing box comprising a tubular body of a size to surround the polished rod and having an inwardly projecting shoulder therein, said body having a tapered portion extending downwardly from the shoulder, a flexible packing gland 40 in the lower portion of the body around the polished rod, said gland having a lower tapered portion complementary to the tapered portion of the body and cooperating therewith and having an angularly disposed flange on the outer periphery thereof of a size to rest on said shoulder, said 45 packing gland having an arcuately shaped circumferential groove in the inner periphery thereof forming an oil reservoir around the polished rod, said groove extending for at least one-third of the longitudinal length of the gland, a plurality of super-imposed conical shaped packing rings in the body above the packing gland around the polished rod, and a compression member above the packing rings of a size to move in the body and compress the packing rings and packing gland, an adjustable sleeve 50 threadedly secured to the body and adapted to control the pressure of the compression member against the packing rings, and means to preclude accidental loosening of the adjustable sleeve.
